(57) **CLAIM**

The ornamental design for a combination artificial turf sample kit and instruction sheets, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a left perspective view of a kit of a combination artificial turf sample kit and instruction sheets showing the new design, shown separately to show aspects of the design that are not visible when combined;

FIG. 2 is a right perspective view thereof;

FIG. 3 is a top view thereof;

FIG. 4 is a top view of an instruction sheet of the combination artificial turf sample kit and instruction sheets, shown separately to show aspects of the design that are not visible when combined;

FIG. 5 is a top view of another instruction sheet of the combination artificial turf sample kit and instruction sheets, shown separately to show aspects of the design that are not visible when combined; and,

FIG. 6 is a top view of another instruction sheet of the combination artificial turf sample kit and instruction sheets, shown separately to show aspects of the design that are not visible when combined.

The broken lines showing the carrying case of the kit form no part of the claimed design.
